UNITED STATES PATENT OFFICE.

FRANK M. BELL, OF EL PASO, TEXAS.

AERIAL PROJECTILE AND LAUNCHING MECHANISM THEREFOR.

1,200,697.

Specification of Letters Patent.

Patented Oct. 10, 1916.

Application filed November 11, 1911. Serial No. 659,808.

To all whom it may concern:

Be it known that I, FRANK M. BELL, a citizen of the United States, and a resident of the city of El Paso, in the State of Texas, have invented a new and useful Aerial Projectile and Launching Mechanism Therefor, of which the following is a specification.

My invention relates to aerial projectiles or torpedoes and mechanism for launching them from aeroplanes or other air craft.

The object of my invention is to provide a projectile of the class described which can be dropped accurately upon the object to be struck independently of the speed or height of the aeroplane or the wind or air currents between the aeroplane and the object.

With the above object in view my invention comprises a projectile having self contained or attached guiding means and a launching mechanism therefor whereby the projectile will strike the spot which is directly under the aeroplane at the moment the projectile is launched irrespective of the height or speed of the aeroplane.

It is well known that the trajectory of an ordinary projectile or weight dropped from a moving support is influenced by at least three factors, viz: the height of the support, its speed and direction of movement and the resistance of the atmosphere. Therefore to cause an ordinary projectile to strike a desired object it is necessary for the aviator to maintain his aeroplane in a certain fixed course and to determine by elaborate calculations the exact point in space at which the resultant trajectory of a released projectile will give the desired result. Exhaustive experiments have demonstrated that by this method accurate results are impossible. With my invention, however, it is only necessary for the aviator to direct his aeroplane over the object to be struck and release his projectile at the moment the object is directly under him. To better determine the point directly beneath him, he may if desired employ a telescope mounted in the usual manner on a universal joint to maintain it vertical, but quite accurate results may be obtained without such apparatus.

A further object of my invention is to provide a projectile containing an explosive charge, with means for exploding the charge by its impact with the object struck.

A further object of my invention is to provide a projectile of the class described with means for preventing its accidental discharge under all circumstances but which will not interfere with its discharge when properly launched or projected.

A preferred embodiment of my invention is illustrated in the accompanying drawings and will now be described.

In the said drawings: Figure 1 is a side elevation of an aeroplane equipped with my improved launching apparatus. Fig. 2 is a plan view of the launching screen showing the position in which the projectile is suspended. Fig. 3 is an enlarged detail showing the manner of supporting the projectile. Fig. 4 is an elevation of the projectile in flight. Fig. 5 is a vertical section of the projectile on an enlarged scale. Figs. 6, 7 and 8 are transverse sectional views on the correspondingly numbered lines of Fig. 5 looking in the direction of the respective arrows, and, Fig. 9 is a diagrammatic view showing the action of the projectile in the air and its trajectory.

Referring now to the drawings in which like characters indicate like parts throughout the several views, and particularly to Figs. 4 and 5, 10 indicates the outer shell of the projectile which is substantially cylindrical in cross section for the major portion of its length and is provided with an integral conical point 11. Extending from end to end of the outer surface of the cylindrical portion of the shell are spiral grooves 12, here shown as three in number and of a pitch to extend about half way around the projectile. The grooves 12 are preferably cut so that their upper edges are at right angles to the surface of the projectile while their lower edges are cut away to permit the air to readily enter the grooves.

The projectile is preferably loaded with an explosive charge as indicated at 13, which fills the space between the outer shell 10 and an inner tube 14 in which is arranged the firing mechanism, as will be later described. The tube is attached at its upper end to a flat ring 15 which is screwed into the open end of the shell 10 to a distance somewhat below its upper edge as shown in Fig. 5. Projecting upwardly from the bottom of the cavity of the projectile are three ribs or webs 16 which engage the outer surface of the tube 14 to hold it in place, and in the center of the bottom is a guide pin 17, also integral

- with the outer shell 10, which projects into the tube 14. Centered on the pin 17 and supported by three rods 18 from the top cap 19 of the projectile is a plate 20 having three countersunk holes 21 in which the percussion caps 22 for igniting the explosive charge are placed with their ends projecting into the portion of the charge which lies between the guide webs 16.
- 10 Slidingly mounted on the rods 18 and normally maintained at the top of tube 14 by a mechanism which will now be described, is a firing plate 23 carrying three firing pins 24 which register with the holes 21 and when the plate is driven to the bottom of the shell by the impact of the projectile with the object struck, strike and explode the caps 22 thereby exploding the charge. The plate 23 is provided with a central projection 25 terminating in conical point 26 which centers in a similar recess 27 in the center of the cap 19. The projection 25 is provided with an annular groove in which engage the curved ends of two small arms 28 pivoted to the under face of the cap 19 as shown in Fig. 6, which arms are held in the groove by means of light springs 29, also attached to the cap 19. Pivoted to the under side of the cap 19 near its outer edge are two levers 30 having weighted ends 31, and connecting the levers 30 and the arms 28 are links 32 so that outward movement of the weights 31 will withdraw the arms 28 from engagement with the groove. The ends of the levers 30 opposite the weights 31 are sector shaped and provided with ratchet teeth 33 with which pawls 34 pivoted on the cap 19 engage, the arrangement of the pawls and ratchets being such that the weights can move freely outward but cannot be again drawn inward by the springs 29. Also supporting the plate 23 are two small brittle wires 35 set in the cap 19 and provided with hooked ends which engage under the edge of the plate 23. The wires 35 are strong enough to sustain the plate while the projectile is falling but are readily broken by the momentum of the plate when the projectile is checked by striking an object.
- 40 Attached to the upper surface of the cap 19, at its middle point, by means of a ball and socket joint 36 preferably provided with bearing balls to reduce friction, is a stem or tail 37 provided at its outer end with three vanes 38. The joint 36 permits the stem 37 to move relatively to the shell in any direction to an angle of about 120 degrees and also permits free relative rotation of the shell and stem in any position. Also attached to the upper face of the cap 19 near its outer edge are three short chains 39 of equal length terminating in rings by which the projectile is suspended beneath the aeroplane.
- 50 For properly launching the projectile the mechanism illustrated in Figs. 1, 2 and 3 is provided which mechanism will now be described. Attached to the underside of the aeroplane in any suitable manner is a hook 40 of the type commonly known as a "snatch-block" hook. As shown in Fig. 3 this hook comprises a body portion attached to the aeroplane and provided with a pivoted, curved piece 41 which is slipped through the rings of the chains 39. The free end of the piece 41 is caught by a hooked latch 42 also pivoted to the body portion of the hook. The weight of the projectile holds the piece 41 and latch 42 in engagement. For releasing the latch, a pull cord 43 is provided, which may, if desired, be connected to a lever 44 arranged adjacent the operator's seat. Also attached to the underside of the aeroplane in a position to inclose the projectile when it is suspended by the hook 40 is a V-shaped screen 45 of fine mesh wire cloth arranged with its apex toward the front of the machine and with its sides projecting below and to the rear of the suspended projectile. The purpose of this screen is to break the force of the air against the projectile so that it will hang vertically in proper position for launching when the machine is in motion as will be hereinafter described. It has been found by experiment that a solid screen causes a vacuum or rarefaction of the air behind the screen which also interferes with the proper launching of the projectile, whereas with the wire mesh screen the air is practically still or rather carried along with the aeroplane.
- 55 The operation of the device will now be described. In Fig. 9 I have illustrated diagrammatically the course of the projectile through the air. Let it be assumed that the aeroplane is moving in the direction indicated by the arrow and that the projectile has been released in a vertical position by means of the lever 44. The projectile is moving forward at a speed proportional to the speed of the machine due to its inertia and as soon as its lower end emerges from behind the screen 45 it meets the resistance of the comparatively still air and the projectile is deflected from its vertical position to an inclined position, the angle of which is proportional to the speed of the aeroplane. The deflection of the projectile by the resistance of the air is augmented, as will be readily understood by the deflection of the air from its tapered lower end. As soon as the tail 37 comes from behind the screen it will be caught by the air and as it is very light compared with the shell it will be swept back as far as the joint 36 will permit and will thereafter tend to maintain a position in line with the movement of the projectile relative to the air. In Fig. 9 I have shown at *a* the position the projectile assumes when it has entirely emerged from behind the screen 45,
- 65 For properly launching the projectile the

and by the dotted lines indicated the paths of movement of the lower and upper ends of the shell and the end of the stem or tail. After the projectile has been launched as described it is acted upon by two forces, one of its momentum in the direction of movement of the aeroplane, which force is rapidly diminishing due to the resistance of the air and the other, the attraction of gravity which causes the projectile to drop with a rapidly increasing velocity, but the air acting in the spiral grooves 27 in the surface of the shell, causes the shell to rotate on its longitudinal axis after the manner of a projectile fired from a rifled gun barrel, and the rotation of the projectile causes its movement due to the factor of gravity to tend toward the line of its longitudinal axis instead of straight downward. When the increasing rearwardly acting force becomes greater than the diminishing forwardly acting force the projectile will begin to move rearwardly as indicated at *b* and *c* in Fig. 9 and thereafter the projectile will be affected only by the force of gravity and the resistance of the atmosphere. The joint 36 between the shell and the tail permits the shell to rotate relatively to the tail and thereby not interfere with the retarding effect of the tail on the upper end of the shell, so that the tail acts as a guide and prevents the projectile turning over or being otherwise deflected from its course by any unevenness in its loading or other cause. The retardation of the upper end of the shell by the action of the tail also causes the projectile to gradually assume a vertical position and by properly proportioning the length of the tail and size of the vanes to the size and weight of the shell the projectile will assume a vertical position at a point directly under the point at which it was released. After the projectile assumes a vertical position it will drop in a vertical line unaffected by wind or air currents. The rapid rotation of the shell will develop an envelop of "neutral" air in exactly the same manner as a projectile fired from a rifled cannon and the guiding stem will maintain it vertical. It is obvious from the above that the projectile will always strike at a point directly under the point of release irrespective of the speed of the aeroplane. The greater the speed, the greater will be the inclination given the projectile by the resistance of the air when it leaves the screen and therefore although its forward momentum is greater it will return a correspondingly greater distance before it assumes a vertical position.

60 I have shown the shell as loaded with an explosive charge but it is obvious that a solid shell may be employed if desired. When an exploding shell is used it is essential that it be provided with a safety device that will absolutely prevent its exploding accidentally. As is well known aeroplanes not infrequently fall from considerable heights and were the explosive projectile not provided with some means for preventing their explosion from impact alone their use would be a menace not only to the aviator but to the entire camp. With my improved firing device the firing plate cannot reach the caps until the projectile has fallen far enough for the projectile to develop a sufficiently rapid rotation for the centrifugal force of the weights 31 to overcome the tension of the springs 29 and draw the arms 28 out of the groove in the projection 25. After the arms 28 release the firing plate it is supported by the brittle wires 35 and the point 26 prevents its tilting and binding the rods 18 so that when the projectile strikes and the firing plate breaks the wires it will move freely on the rods to the bottom of the shell and explode the caps. The pawls 34 are not necessary to hold the arms 28 out of engagement but are provided to prevent the arms being jarred into engagement by the impact of the shell before the firing plate breaks the wires 90 35. If it be desired that the projectile penetrate the object struck before exploding, the lower portion of the shell, between the webs 16 may be filled with a slow burning powder.

95 While I have shown my invention in connection with an aeroplane, it is obvious that it is equally applicable to balloons and dirigible air ships. It is also obvious that my improved firing mechanism, while especially applicable to aerial projectiles may be used 100 in ordinary projectiles to be fired from rifled cannon. It is also to be understood that, while I have illustrated the preferred form of my invention, the details of construction herein disclosed may be widely varied without departing from the spirit and scope of my invention. For instance instead of the grooves in the outer surface of the shell I may employ spiral ribs.

110 I claim:

1. A projectile comprising a body portion and a guiding device pivotally and rotatably connected thereto.
2. A projectile comprising a body portion, a guiding stem and a joint between said body portion and said stem permitting relative angular and rotative movements of said body portion and stem.
3. A projectile comprising a substantially cylindrical body portion, a stem having a 115 guide vane and a joint between said body portion and said stem in line with the longitudinal axis of said body portion and permitting relative angular and rotative movements of said body portion and said stem.
4. A projectile comprising a body portion having means for causing it to rotate while moving through the air, a guiding stem and a joint between said stem and body portion permitting relative angular 120 movements of said body portion and said stem.
5. A projectile comprising a body portion having means for causing it to rotate while moving through the air, a guiding stem and a joint between said stem and body portion permitting relative angular 125 movements of said body portion and said stem.

65

- and rotative movements of said body portion and stem.
5. A projectile comprising a body portion having a spiral air engaging face formed on its outer surface, a guiding stem and a joint between said stem and said body portion permitting relative angular and rotative movements of said stem and body portion.
- 10 6. A projectile comprising a substantially cylindrical body portion having a pointed end and spiral groove in its cylindrical surface, a stem provided with guiding vanes and a joint between said stem and body portion in line with the longitudinal axis of said body portion and permitting relative angular and rotative movements of said body portion and said stem.
7. A projectile comprising a shell containing an explosive charge, means actuated by the impact of one end of said shell for exploding said charge, a stem provided with guide vanes, and a joint between said stem and the opposite end of said shell permitting relative angular and rotative movements of said shell and stem.
- 15 8. A projectile adapted to be discharged from moving air craft, comprising a body portion, means for rotating the same and guiding means for causing the rotation of said projectile to direct it in an opposite direction to its movement from its bodily momentum.
9. A projectile adapted to be discharged from moving air craft, comprising a body portion, means for rotating the same and guiding means for causing the rotation of said projectile to direct it in an opposite direction to its movement from its bodily momentum, and to an extent proportional to its momentum.

In testimony whereof I have hereunto set my hand this 10th day of November, 1911.

FRANK M. BELL.
